UNITED STATES PATENT OFFICE

170,896

APRON

Frances Warren, Pittsburgh, Pa.

Application May 5, 1953, Serial No. 24,865

Term of patent 7 years

(Cl. D3—26)

To all whom it may concern:

Be it known that I, Frances Warren, have invented a new, original, and ornamental Design for Aprons, of which the following is a specification, reference being had to the accompanying drawing forming a part hereof.

Figure 1 is a face view of an apron, embodying my design;

Fig. 2 is a rear view thereof,

Fig. 3 is a partial edge view of Fig. 1, looking from the right, and

Fig. 4 is an enlarged edge view of my design, looking toward the left hand edge of Fig. 2, as it appears in use with the pouch of the apron filled.

I claim:

The ornamental design for an apron, as shown and described.

FRANCES WARREN.
